(57) **CLAIM**

The ornamental design for a truck bumper component, as shown and described.

DESCRIPTION

FIG. 1 is a front right perspective view of a truck bumper component showing our new design;

FIG. 2 is a front elevational view of the truck bumper component of FIG. 1;

FIG. 3 is a rear elevational view of the truck bumper component of FIG. 1;

FIG. 4 is a top plan view of the truck bumper component of FIG. 1;

FIG. 5 is a bottom plan view of the truck bumper component of FIG. 1;

FIG. 6 is a right side elevational view of the truck bumper component of FIG. 1; and,

FIG. 7 is a left side elevational view of the truck bumper component of FIG. 1.

The broken line showing of supporting structure is for the purpose of illustrating environmental structure and forms no part of the claimed design.

The truck bumper component shown in FIGS. 1-7 illustrates a first embodiment of our novel design suitable for use on the right side of a truck. Our novel design also includes a second embodiment suitable for use on the left side of the truck, which is mirror symmetrical to FIGS. 1-7 and, therefore, not separately illustrated.
